United States Patent Office

Des. 203,828
Patented Feb. 22, 1966

203,828

WEATHER SHIELD TERMINAL BOX

Donald H. Wells, Oregon, Ohio, assignor to S & A Electronics, Inc., Oregon, Ohio, a corporation of Ohio

Filed Mar. 10, 1965, Ser. No. 84,188

Term of patent 14 years

(Cl. D26—5)

FIG. 1

FIG. 3

FIG. 2

FIG. 1 is a front perspective view of a weather shield terminal box, showing my new design;

FIG. 2 is a rear perspective view thereof; and

FIG. 3 is a perspective view thereof in an open position. I claim:

The ornamental design for a weather shield terminal box, substantially as shown and described.
